UNITED STATES PATENT OFFICE.

CHARLES O. WOOD, OF CHAMBERSBURG, PENNSYLVANIA.

MOLDING-JACKET.

1,077,779.

Specification of Letters Patent. Patented Nov. 4, 1913.

Application filed March 5, 1913. Serial No. 752,096.

To all whom it may concern:

Be it known that I, CHARLES O. Wood, of Chambersburg, in the county of Franklin and in the State of Pennsylvania, have invented a certain new and useful Improvement in Molding-Jackets, and do hereby declare that the following is a full, clear, and exact description thereof.

The object of my invention has been to provide a jacket for use in molding, which shall have among others, any or all of the following advantages: that it shall be capable of being put upon or about a sand mold in such a way that its parts shall accurately and effectively fit and sustain the sides of said mold; that its parts or sides shall be flexibly or jointedly connected so as to adapt themselves to the sides of the mold however irregular, and that it shall be cheap, durable and practical in construction. And to such ends my invention consists in the jacket for use in molding hereinafter specified.

In the accompanying drawings Figures 1, 2 and 3 are respectively, a bottom plan view, a side elevation and an end elevation of a jacket embodying my invention. Figs. 4 and 5 are enlarged plan views of different forms of connection between the sides of my jacket. Fig. 6 is a side elevation of Fig. 5.

My invention is capable of embodiment in many different forms and the illustrated embodiment is therefore to be regarded as typical only of many possible embodiments.

Jackets embodying my invention are capable of use in a variety of ways, and while I shall illustrate the use of one embodiment of my invention by a specific example, such example is to be regarded as typical only.

As an example of foundry practice involving the use of a form of my jacket, it may be assumed that a mold has been made of sand or other suitable material consisting of an upper part, or cope and a lower part, or drag, containing within and between them the cavity of the shape of the article to be cast. After the mold has been formed, if it is properly formed, it does not need anything to sustain it except at the time when the metal is poured into the mold and until the metal or other substance to be cast has set or begun to set. It is, however, customary to remove the flask from the mold, so that the flask can be used for the making of other molds and to put a temporary jacket about the sand mold just before pouring in

the metal, removing it as soon as the metal has set and using the jacket for casting in other molds. My jacket is especially intended for such use as that of the jacket.

My jacket in the form illustrated in Figs. 1, 2 and 3 consists of long sides 1 and short sides 2, which are so connected that they can have movement relative to each other, and preferably universal movement. In this form of my invention the connection consists of straps 3, which in the present instance are illustrated as formed of leather or asbestos and are secured to the sides as by bolts 4. The sides are preferably trapezoidal in form and the straps are preferably so connected to them that my jacket will normally have the form of a truncated pyramid, so as to adapt it for use on a tapering mold. These sides may, however, consist of parallelograms for use with a mold whose sides are vertical.

Assuming the mold to be in the form of the frustum of a pyramid, my jacket is simply pressed downward along the sides of the mold until all of the sides of the jacket bear firmly against the sides of the mold. Because of the flexible connection between the sides, a single one of my jackets can fit molds of a wide variety of dimensions, proportions and defects.

If the mold only varies from the normal shape of my jacket by any reasonable amount the variable connections will permit the necessary accommodation. If, however, the mold be substantially shorter than the jacket, it is only necessary to press one of the end plates of my jacket downward below the level of the sides, when the diagonal position of the connecting straps will in effect cause the shortening of the jacket. In the same manner an adjustment can be made for the unusual difference in width of the jacket.

In the form of my invention shown in Fig. 4, the connection consists of plates 5 secured to the flask sides 6 and having ears 7 standing in substantially parallel relation. The bolt 8 passes loosely through the said ears so as to permit great freedom of motion of the bolt relative to the ears. I preferably provide a coil spring 9 surrounding the bolt and bearing between the ears to tend to keep the sides 6 separated and in their normal position.

In the form of my invention shown in

Fig. 5, I make the connection in the form of a double hinge, the connection, as shown, consisting of plates 10 secured to the sides 11 and carrying pairs of parallel ears 12 which support pins 13. The link 14 lies between the ears of each pair and connects the pins 13, the link having holes larger than the pins and being thinner than the space between the ears so as to permit great freedom of motion.

It will be observed that my molding jacket is capable of fitting molds of widely different variety, whether having vertical or tapering sides, whether the sides are parallel or not, whether the sides are of equal dimensions (within considerable limits), or whether or not there be other defects present. It will also be observed that my jacket is simple and cheap in construction and is durable.

I claim:

1. In a molding jacket or casing the combination of sides, and connections between the ends of adjacent sides permitting relative movement in more than one plane, every side of the jacket being movable relative to each of its neighbors.

2. In a molding jacket or casing the combination of sides, and connections between the ends of adjacent sides permitting relative movement about more than one axis, every side of the jacket being movable relative to each of its neighbors.

3. A molding jacket consisting of a plurality of sides and a universal connection between each two sides.

4. A molding jacket consisting of a plurality of sides and a flexible connection between the adjacent ends of each pair of sides.

5. A molding jacket consisting of a plurality of sides and a connection between the ends of said sides permitting relative vertical adjustment thereof.

45 6. A molding jacket consisting of a plurality of sides and a connection between the ends of each two adjacent sides permitting relative horizontal adjustment thereof.

50 7. A molding jacket consisting of a plurality of sides and a connection between the ends of each two adjacent sides permitting relative bodily displacement.

8. A molding jacket consisting of a plurality of sides and a connection between the ends of said sides permitting relative movement to different levels.

60 9. A molding jacket consisting of the combination of sides and means universally connecting adjacent ends of each pair of sides.

10. A molding jacket consisting of the combination of sides, and a connection between the adjacent ends of each pair of sides, said connection being capable of movement relative to each of the sides which

it connects, to permit variations of size or contour.

11. A molding jacket consisting of the combination of sides, and a connection between the adjacent ends of each pair of sides, said connection, as a whole, being capable of movement relative to each of the sides which it connects.

12. A molding jacket consisting of the combination of sides, and a connection between the adjacent ends of each pair of sides, said connection having a substantially universal connection with each end of a side to which it is connected.

13. A molding jacket consisting of the combination of sides, and a connection between the adjacent ends of each pair of sides, said connection having a substantially universal connection with each end of a side with which it is connected, said sides being spaced apart when said connection is at normal length.

14. A molding jacket consisting of a plurality of sides and a universal connection between two adjacent sides at one or more corners.

15. A molding jacket consisting of a plurality of sides and a flexible connection between two adjacent sides at one or more corners.

16. In a molding jacket or casing the combination of sides and a connection between two adjacent sides at one or more corners, permitting relative movement in more than one plane.

17. A molding jacket consisting of four connected sides and provided with means permitting two opposite sides to recede from each other and at the same time causing the other two opposite sides to approach each other.

18. A molding jacket for supporting the sides of a sand mold after the molding flask has been removed, comprising a plurality of sides and means for connecting two or more sides together to permit, without adjustment, either the alteration of the relative inclination of the sides, the size, or shape, or both size and shape of the space inclosed by said sides, whereby the jacket will be automatically accommodated to variations of the sand mold.

19. A molding jacket for supporting the sides of a sand mold after the molding flask has been removed, comprising a plurality of sides and connections between two adjacent sides at two or more corners to permit, without adjustment, either the alteration of the relative inclination of the sides, the size, or the shape, or both size and shape

125 of the space inclosed by said sides, whereby the jacket will be automatically accommodated to variations of the sand mold.

20. A molding jacket consisting of a plurality of sides and a double hinge connec-

tion between two adjacent sides at one or more corners.

21. A molding jacket consisting of a plurality of sides and a double hinge connection between two adjacent sides at one or more corners, said connection including a link having a slight amount of universal movement.

In testimony that I claim the foregoing I have hereunto set my hand.

CHARLES O. WOOD.
